John T. Utecht,

BY *Richard Lewin,*

ATTORNEY

UNITED STATES PATENT OFFICE.

JOHN T. UTECHT, OF DEPEW, NEW YORK.

SASH-HOLDER.

1,250,725.

Specification of Letters Patent. Patented Dec. 18, 1917.

Application filed June 21, 1917. Serial No. 176,136.

To all whom it may concern:

Be it known that I, JOHN T. UTECHT, a citizen of the United States, residing at Depew, in the county of Erie and State of New York, have invented certain new and useful Improvements in Sash-Holders, of which the following is a specification.

This invention relates to an improved sash holder of the spring actuated type and the principal object of the invention is to provide a device of the character described which may be mounted in a pocket formed in the side portion of the sash and which will be yieldably held in an extended position to engage the window frame and thus provide means for holding the sash in an adjusted position through frictional engagement with the window frame.

Another object of the invention is to provide improved means for connecting the springs with the frame engaging strip, this means being so constructed that the spring will be securely connected with the strip and thus prevented from slipping loose.

Another object of the invention is to provide improved means for securing the springs in sockets formed in the sash and to further so construct the frame engaging strip that openings will be formed through which a punch can be inserted to permit the spring fasteners to be driven tightly into the window sash.

This invention is illustrated in the accompanying drawings, wherein:—

Fig. 1 is a view in elevation showing a portion of a window sash provided with the improved device,

Fig. 2 is an enlarged longitudinal sectional view through a portion of a window sash having the improved device connected therewith,

Fig. 3 is a view showing the improved device in elevation looking at the inner face of the strip, and

Fig. 4 is a transverse sectional view taken along the line 4—4 of Fig. 2.

The window sash indicated in general by the numeral 10 will have each side bar provided with a longitudinally extending cutout forming a pocket 12 from which there extends wells or sockets 13 to receive the springs 14. These springs 14 carry fasteners 15 which fasteners have their heads engaging the coils of the springs as shown in Figs. 2 and 4. The window frame engaging strip 16 extends longitudinally of

the side bar 11 and has its end portion 17 bent to extend into the upper and lower end portions of the pocket 12 thus permitting the window sash to have the proper sliding movement in the frame without danger of the friction strip at each side catching upon rough places in the frame. At points in alignment with the wells 13, this strip 16 will be provided with side tongues 65 or arms 18 extending into the pocket 12 upon opposite sides of the springs 14 and serving as guides for the springs and preventing transverse play thereof as clearly shown in Fig. 4. Tongues or spring fasteners 19 are struck from the strip and are bent inwardly to provide hooks engaging the coils of the springs thus securely connecting the springs with the strip and preventing danger of the strip becoming disconnected from the springs. It should be noted that when these tongues are struck from the strip and bent inwardly to form the hooks, they provide openings 20 through which a punch 70 can be passed to engage the heads of the fasteners when driving the fasteners into the window sash.

It will thus be seen that this device can be very easily and quickly put in place after the pocket 12 and sockets 13 have been 85 formed and it will be further seen that when in place, they will be securely fastened but permitted to have upward movement under action of the springs. This will cause the strip to have binding engagement with the 90 window frame and through the medium of the device, the window may be held in a raised position.

I have therefore provided a device of the character described which will be very efficient in operation and which will be very strong and durable. I have further provided a device of the character described which can be formed principally of sheet metal cut from a blank and bent to assume 100 the proper shape.

What is claimed is:—

1. A window sash having its side bar provided with a longitudinally extending cutout leading from the edge face and forming 105 a pocket, the pocket being provided with extensions forming wells, a gripping strip extending longitudinally of the pocket and having tongues struck therefrom and bent to provide spring engaging elements, side 110 arms extending from the strip into the pocket, springs positioned between the side

- arms and having their outer convolutions engaged by the engaging elements, and fasteners in said wells having prongs embedded in the window sash and heads engaged by 5 said springs.
2. A window sash provided with a longitudinally extending cutout forming a pocket, a frame engaging strip extending longitudinally of the pocket and provided with side 10 arms extending into the pocket, tongues struck from the strip and bent inwardly to provide spring-engaging hooks, springs positioned in the pockets between the side arms and having their outer convolutions engaged 15 by the hooks, and fasteners having prongs embedded in the sash and heads engaging the inner convolutions of the springs.
3. A window sash having a pocket formed therein, a frame engaging strip extending longitudinally of the pocket, tongues struck from the strip and bent to provide spring 20 engaging elements, and openings in the strip, springs having their outer end portions engaged by the spring engaging elements, and 25 fasteners connected with the inner end portions of the springs and provided with penetrating prongs, the fasteners being positioned for access through the openings
- formed when striking said spring engaging elements from the strip.
4. A device of the character described comprising a body having an opening therein, spring gripping tongues extending from the body upon opposite sides of the opening, a spring positioned between and gripped by 30 the spring gripping means, and a fastener carried by the spring, access to the fastener being had through the opening in the body.
5. A window sash having a side bar, a gripping strip extending longitudinally of 35 the side bar and having tongues extending therefrom and bent to provide spring engaging elements, a spring having its outer end portion engaged by the spring engaging elements, and a fastener gripped by the 40 spring and positioned for access through the opening formed in the gripping strip when the tongues forming the spring engaging elements are struck therefrom.

In testimony whereof I affix my signature 45 in presence of two witnesses,

JOHN T. UTECHT.

Witnesses:

FRANK UTECHT,
S. JAY OHLART.
